[57] CLAIM

The ornamental design for a combined educational game spinner and blocks therefor, substantially as shown and described.

DESCRIPTION

FIG. 1 is a perspective view of a combined educational game spinner and blocks therefor, showing my new design;

FIG. 2 is a front elevational view;

FIG. 3 is a side elevational view as seen from the left of FIG. 2; the right elevational view is the same but reversed;

FIG. 4 is a rear elevational view;

FIG. 5 is a top plan view;

FIG. 6 is a bottom plan view.
